UNITED STATES PATENT OFFICE.

KARL E. PEILLER AND EDWARD H. LORENZ, OF WEST HARTFORD, CONNECTICUT,
ASSIGNORS TO HARTFORD-FAIRMONT COMPANY, OF CANAJOHARIE, NEW
YORK, A CORPORATION OF NEW YORK.

GLASS-WORKING MACHINE.

1,316,550.

Specification of Letters Patent. Patented Sept. 16, 1919.

Application filed November 20, 1917. Serial No. 202,984.

To all whom it may concern:

Be it known that we, KARL E. PEILLER and EDWARD H. LORENZ, citizens of the United States, residing at West Hartford, in the 5 county of Hartford and State of Connecticut, have invented new and useful Improvements in Glass-Working Machines, of which the following is a specification.

This invention relates to machines for 10 forming glassware, and particularly to the organization of such machines in duplex or multiple arrangement, whereby a plurality of such machines may be operated in coördination as a unitary machine, and 15 either of them may also be stopped, or operated independently of the other.

The objects of the invention are to provide an organized arrangement of such machines driven by a single driving medium; 20 and if desired supplied with molten glass from the same source of supply; to provide means and mechanism for operating and controlling the machines either separately or intermittently, so as to stop either machine while continuing the full and complete operation and production of the other machine; to restore the stopped machine to 25 operation in synchronism and coördination with the other machine; to provide interlocking controlling devices for the respective parts, for insuring proper sequence of their operation, and for stopping, in a safe position, such parts as might otherwise collide with or interfere with each other, in 30 case of failure of operation, or in case of abnormal or incomplete operation.

This invention is herein illustrated and described as being embodied in a duplex automatic machine organized as a single 40 unit, mounted on the same base and driven by the same driving means. The molds of both machines are, or may be, fed with charges of glass from the same feeding mechanism. Each of these machines is 45 otherwise complete in itself, and may, in accordance with this invention, be operated either separately or in coördination with the other machine. Each machine is provided with a rotatable table, carrying molds of the 50 required number and size and form for the glassware to be produced. The tables

are intermittently advanced and stopped and locked at stationary positions or stations at which its various molds are presented to their charge receiving, pressing and delivering positions, respectively. Interlocking mechanism is provided for controlling the operations, so that either table can be stopped, unlocked and turned in either direction, and its molds changed or adjusted 55 without stopping or interfering with the full productive operation of the other machine. The interlocking mechanism includes safety provisions for stopping either table automatically in a safe position, in 60 case of abnormal operation of the machine, due to failure of the air pressure supply, or otherwise. It also provides for restarting the stopped machine in proper synchronism and coördination with the associated machine, preventing such restarting unless the 65 table is in correct position at one of its proper stations and the parts are otherwise in correct relation to resume their intended functions. This includes means for stop- 70 ping the operation of the pressing plunger, if its associated table fails to operate in proper time, or fails to be stopped in proper position at any station.

Figure 1 of the accompanying drawings 80 shows a side elevation of a pair of machines embodying the invention. The two machines are alike, excepting that one is built right handed and the other is built left handed.

Fig. 2 is a plan, on a larger scale, of the mechanism below the mold table of the left hand machine.

Fig. 3 is a plan of part of the rotating and locking mechanisms of the left hand 90 table, in one position.

Fig. 4 is a plan of part of the left hand table rotating and locking mechanisms, in another position.

Fig. 5 is, on still larger scale, an elevation, 95 with the table and other parts in vertical section on the plane indicated by the line 5—5 on Fig. 2.

Fig. 6 is a partial elevation of the table and operating mechanism, looking from be- 100 tween the machines toward the left hand machine.

Fig. 7 is an elevation looking from the rear and showing parts of the left hand table rotating mechanism.

Fig. 8 is a front elevation of the controlling cams and levers.

Fig. 9 is a side elevation of the controlling cams and levers.

Fig. 10 is a plan of the brake mechanism for retarding the movements of the tables.

10 Fig. 11 is an elevation, looking toward the rear, of the brake controlling mechanism, with parts of the two tables in vertical section.

Fig. 12 is a plan of the mechanism for 15 interlocking one of the tables and its pressing plungers.

Fig. 13 is an elevation of the plunger and table interlocking mechanism.

Fig. 14 is an elevation of the plunger and 20 table interlocking mechanism in a different position.

Figs. 15, 16, 17 and 18 are plan views, showing different relations of the safety interlocking mechanism.

25 Fig. 19 is a front elevation of the valve mechanism, including the devices for manually latching the air controlling piston valves, and coincidentally shutting off the flow of cooling fluid to the plunger.

30 The invention illustrated has a bed 1 supported by which are vertical columns 2 that are connected at their upper ends by a cross beam 3 (Fig. 1). A table 4 carrying the desired number and style of molds 5 is mounted on suitable bearings 6, (Fig. 5) so as to rotate about each column, and a pressing mechanism 7 for each table is supported by the overhead cross beam above the paths of the molds. The machine is actuated by the 35 rotation of a drive shaft 8 which extends horizontally from side to side across the machines above the bed and drives both machines. As the table rotating, plunger reciprocating, and interlocking and controlling mechanisms of the two machines are 40 similar, only those for the left hand machine are herein illustrated and described in detail.

The table is intermittently advanced by 50 the following mechanism. Mounted on a vertically held stud 9, Fig. 5, above the bed and below the table near one side of the machine, is a worm wheel 10 that is engaged by a worm 11 on the drive shaft. Keyed on 55 the hub 12 (Fig. 5) of this worm wheel are two cams 13 and 14. The cam 13 acts against a roller 15 (Fig. 2) carried by a rocker yoke 16, the hub 17 of which is mounted on a vertical post 18 supported by a frame 19 fastened 60 on the bed near the back of the machine, (Figs. 2, 7). The cam 14 acts against a roll 20 carried by the rocker yoke to hold back the table as it approaches its stopping position, overcoming its momentum and preventing it from passing its stopping posi-

tions, also to insure positive return of the rotator parts. A spring 21 is arranged to hold the rocker roll 15 back against the cam 13. The other end of the spring is attached to an arm 143, which is adjustably clamped 70 on the part 144, the upper end of which is connected with the top of the stud 9 by a brace 145. Mounted on the post 18 and adjustably fastened to the hub of the rocker yoke is a rocker arm 22, (Figs. 2, 7,) which 75 is connected by a link 23 with a table rotator arm 24 which is pivotally mounted on the hub 25 of the mold table 4 (Fig. 2, 5). In the end of the rotator arm is a bolt 26, a spring 27 being arranged to normally project the bolt outwardly from the arm, into one of the index notches 28, formed in the inner sides of index blocks 29, fastened to the under side of the table at equal distances apart around the table, (Figs. 5 and 80 6) herein shown to be eight in number spaced 45 degrees apart, for tables carrying eight molds. In normal operation the bolt 26 is projected into a notch 28 and the rotator arm is swung forward 45 degrees, 85 advancing the mold table one step. Then the bolt 26 is positively withdrawn, and the rotator arm is returned to its first position, with its bolt in line with the next notch. These notches are also engaged by the locking bolt 40 herein after described, to lock and hold the table at its eight stopping positions or stations. The sides of the notches and of the coengaging ends of the bolts 26 and 40 90 are beveled to facilitate entrance to the bolts 100 and especially to enable the entering movement of the locking bolt 40 to move the table slightly forward or back to settle it in exact position at the respective stopping stations. This bevel or taper is, however, not sufficiently abrupt to allow the bolts to be displaced or retracted from the notches by relative movement of the table and the rotator mechanism, thus enabling the rotator bolt to be utilized for advancing the table by a 105 graduated movement which is first accelerated and then retarded. Mold tables, especially when loaded with molds, are externally heavy, and for commercial production it is necessary to advance the table in a very 110 short time, from one to two seconds. To make this rapid advancing movement smoothly without shock or jar, it is desirable to start the table slowly, accelerating its speed for about half its movement, and then 115 retarding its speed and stopping it at its next locking position. The rotator mechanism here shown is adapted to impart such a controlled advancing movement during which the relatively slight taper of the bolt 120 26 enables it to remain seated in its notch 28 against the displacing tendencies of the accelerating and retarding action. The rotator bolt 26 being thus firmly seated in an index notch 28, the first accelerating half of 125 130

the advancing movement is imparted by the cam 13 against the roller 15. The momentum of the table would ordinarily carry it from this point, past the next stopping position. Therefore, during about the last half of its movement the table is retarded, so as to stop without shock approximately at its index locking position. This retarding movement is effected by the cam 14 operated 10 against the roller 20, assisted if necessary by brake mechanism, as hereafter described (Figs. 10 and 11).

Inasmuch as the bolts 26 and 40 are not self retracting from their notches 28 for 15 the reasons above described, other means are provided for positively retracting those bolts and also for controlling their positions at all times, independently of the notches 28, and these rotator and bolt controlling mechanisms are so coöordinated and interlocked as to insure their proper operation under normal conditions, while also safeguarding the machine against injurious operation under abnormal conditions.

25 For retracting the rotator bolt 26 and controlling its position at all portions of the forward and backward movement of the rotator arm, a segmental controller 36 is mounted for horizontal swinging movement 30 on the vertical stud 37. The inner guiding surface of the controller 36 engages with a roll 38 on a stud 39 secured to the under side of the rotator bolt 26 (Figs. 2, 3, 4 and 5). When this controller is in a position 35 which retracts the rotator bolt (Figs. 3 and 4) its inner guiding surface is concentric with the axis of the table, so as to hold the bolt in retracted position throughout the returning movement of the rotator arm. The 40 arc formed by the guiding surface is slightly longer than the arc of swinging movement of the rotator bolt roll 38, so as to control the sliding movements of the rotator bolt throughout its entire arc of swinging movement.

The rotator bolt controller 36 is operated normally by the following mechanism:—A worm 30 on the drive shaft 8 meshes with the worm wheel 31 on a vertical cam shaft 50 32, which is supported by a bracket 33 mounted on the bed below the table. A spider 94 supported by the posts 44, 95 and 96 forms a bearing for the upper end of the cam shaft 32. Fastened to this shaft are the 55 control cams (Figs. 8 and 9). The cam 34 engages with the roll 35 on the rotator bolt controller 36, and swings the latter to the extent shown by comparison of Figs. 2 and 3, this movement being timed in proper relation to the forward and back movements 60 of the rotator arm 24, so that in the normal operation of the machine the rotator bolt 26 will be admitted to a notch 28 when the rotator arm 24 is in its retracted position 65 shown in Fig. 2; and will withdraw the ro-

tator bolt from that notch when the rotator arm reaches the end of its forward movement, as shown in Fig. 3. The controller 36 remains in this position during the return movement of the arm 24, so as to hold the 70 rotator bolt 26 in its retracted position during that movement, thereby preventing it from entering any succeeding notch 28 until it again reaches its backward position shown in Fig. 2. Figs. 4, 15 and 18 illustrate a 75 condition in which the table is displaced from normal position, by hand or otherwise, and shows how the controller 36 prevents the bolt 26 from entering the notch 28 in front of it. It will be understood that 80 both of the rotator arms 24 continue to oscillate while either machine is in operation.

The table is locked in position at its different stations by a lock bolt 40 which is 85 slidable in its seat in the upper end of a fixed bracket 41 that is mounted on the bed at the front of the machine. A spring 42 is arranged to pull the bolt outward so that it will enter one of the notches 28 on the underside of the table (Fig. 3). This lock 90 bolt is withdrawn at the proper time to release the table, by the angle lever 43 that is mounted on a post 44 of the frame 33. One end of this lever is forked and engages a stud 45 projecting from the bolt, while the 95 other end has a roll 46 that is held by its connection with the spring 42 in contact with the periphery of the cam 47 on the shaft 32, (Figs. 2, 3, 4). In the ordinary operation of the machine the lock bolt is 100 withdrawn from a notch 28, and about the same time the rotator bolt 26 is allowed to enter another notch 28, this occurring just before the cam 13 begins to advance the rotator arm 24, these positions being shown in 105 Fig. 2. When the rotator arm has swung forward its full extent the lock bolt 40 is allowed by the cam 47 to enter its next notch, and the rotator bolt 26 is withdrawn, as shown in Fig. 3, then the cam 14 and the 110 spring 21 swing the rotator arm back.

A safety interlock is provided between the rotator bolt 26 and the lock bolt 40 (Figs. 4 and 15). On the lock bolt withdrawing lever 43 is a latch 48 the free end 115 of which is pushed away from the lever by a spring 49 against a stop pin 48'. When the controller 36 is pushed over for withdrawing the rotator bolt 26 from a notch, if the lock bolt is prevented from entering a 120 notch 28, as for instance, by reason of the table being out of proper position, the latch 48 due to the abnormal position of the lever 43 will engage the notch 50 in the end of the controller 36 and prevent the latter from 125 swinging outward. Under these conditions the rotator bolt is held out of action, even when the controller 36 is released by its cam 34. This prevents the injurious collision which would result from the rotator bolt 130

engaging the table in any intermediate position of their turning movements when one or both are turning rapidly and sometimes in opposite directions. The controller permits the rotator bolt to engage with the table only when the table is locked at one of its stations, and only when the rotator arm 24 pauses at the rearward end of its stroke.

- To release the table from both of the bolts 10 26 and 40 so that the table may be turned when changing the molds, or adjusting the parts, a releasing hand lever 51 is pivoted at 52^a on the side of the lock bolt supporting bracket 41 (Figs. 2, 6 and 15). This lever 15 is bell cranked and is hung so that when its handle end, which extends out toward the front of the machine, is lifted, its inner end 52 will engage and hold back the lock bolt withdrawing lever 43 and thus hold the lock bolt 20 out of engagement and leave the table free to be rotated by hand. The handle end of this lever 51 may when lifted be sprung over a latch 53, so as to retain the lever in position to hold the lock lever back with the 25 lock bolt withdrawn. When the lock bolt is thus withdrawn and held back, the latch 48 will interlock with the controller 36, and hold the latter as in Figs. 4 and 15, so that the rotator bolt 26 cannot engage the table, 30 and the table will therefore remain stationary, while the rotator arm 24 continues its movement. The effect of this is to prevent throwing the rotator bolt into engagement during its swing, since it can only be thrown 35 in when the table is locked and therefore at the ends of its swing. This prevents the disastrous blow which would result from the operator attempting to start the table rotation when the table is between stations.
- 40 The rotator bolt may also be put out of action independently of the lock bolt. Attached to the controller 36 is an arm 54 to which the rear end of a rod 55 is fastened (Figs. 2, 3, 5 and 17). The front end of this 45 rod is connected with the upper end of an angle lever 56 that is mounted on a bracket 57 secured to the bed near the front of the machine (Figs. 10, 12, 13). The front and lower end of this angle lever is connected 50 with a bar 58 that extends forwardly and has its front end bent to form a treadle 59, which being permanently connected with the controller 36 moves up and down as the controller swings in and out. Also by depressing 55 this treadle as by foot pressure, the controller 36 may be moved in so as to withdraw the rotator bolt 26 from any notch in the table. On the side of the treadle bar 58 is a dog 60 and adapted to engage with 60 that dog is a latch 61 provided with a handle 62 (Figs. 12, 14). This latch may be turned manually by its handle so as to engage the dog, and latch the treadle down (Figs. 14 and 17), which as above explained 65 holds the rotator bolt in retracted position.

The latch 61 is yieldingly retained in its two positions by a spring pressed catch 88 entering V-shaped notches in an arm 89 of the latch 61. (Figs. 12, 13, 14). It is evident, therefore, that by depressing the treadle 59 of either machine with the foot, the table rotating mechanism of that machine can be held out of operation. Also, that when the handle 51 is lifted and the lock bolt 40 is withdrawn, the table rotating mechanism is disconnected.

A brake mechanism, shown in Figs. 10 and 11, may be employed to assist the rotator mechanism in stopping the mold tables when the latter are exceptionally large or 80 heavy, thus lessening the strain and shock upon the table rotating and locking devices. In a groove 63 around the outer edge of each table is a brake band 64. One end of this brake band is connected with an eccentric 85 pin 65 mounted in the swinging end of a link 66 that is pivoted on a stud seated in the support 121 (Fig. 10). The eccentric pin has a handle 68, and extending through a swivel stud 69 projecting from the link, 90 into a fixed stud 70 is a screw threaded rod 71 with a handle 72 (Figs. 10, 11). By turning the handle 72 the link 66 may be swung to give the proper tension to the brake band. By turning the handle 68 of the eccentric pin 65 the brake may be released, as when it is desired to turn the table by hand without disturbing the other adjustments of the brake band.

The other end of the brake band is attached to a link 73 which has a yielding connection by means of a spring 74 with a connecting rod 75 that is joined to a rocker arm 76, on the vertical shaft 77 (Figs. 10, 11). On this shaft is a cam lever 78 having 100 a roll 79 held in engagement with a cam 80 by a spring 81. The cam 80 is adjustably connected with the rotator bolt operating cam 34 on the vertical shaft 32 (Figs. 10, 11). This cam 80 is so timed as to begin to 105 apply the brake at about the middle of the turning movement of the table, that is, when the table has reached its highest speed, and to release the brake when the table has come to rest. The adjustable connection between 110 the cam 80 which applies the brake and the cam 34 which controls the action of the rotator bolt permits the time of applying and releasing the brake with relation to the time of movement of the table to be exactly regulated.

The cross beam 3 supports a pressing mechanism 7 for each machine, which is or may be of any well known type or construction (Fig. 1), and needs no specific description. Each of these pressing mechanisms is operated by a double-acting cylinder 83, the piston of which operates the piston rods 84, by air or other fluid under pressure, under the control of the valve and 125 130

interlocking mechanisms hereinafter described. Each piston rod carries the customary forming plunger 85 and spring plate 86, to the latter of which is attached a mold 5 ring 87 for closing the top of its mold 5, as shown in the right hand machine of Fig. 1, all of which is or may be of well-known construction in glass pressing machines.

The pressing mechanisms of the two machines operate alternately, each table being advanced while its pressing mechanism is in the raised position shown in the left hand machine of Fig. 1.

A valve chest 100 mounted on the bed at the front of the machine is supplied through an inlet pipe 97 with air or other fluid under pressure. A reciprocating piston valve 113 controls the admission of the pressure, through the pipe 90 to the top of the cylinder 83, and through the pipe 91 to the bottom of that cylinder, and releases the pressure therefrom through the exhaust pipes 98 (Figs. 1, 2, 6 and 19). A spring 101 (Fig. 2), mounted in the valve casing, presses the valve in one direction, and the valve is pushed in the opposite direction by one end of an angle lever 102. This lever is pivoted on the post 44 that forms one support of the frame 94, and has a roll 103 engaging a cam 104 on the vertical cam shaft 32 (Figs. 2, 8), which operates the valve 113 that controls the movements of the piston in the cylinder 83. The cam is made in two sections, (Figs. 8, 9), adjustably connected together so as to enable the time movements of that piston to be definitely regulated. When the valve is pushed in by the lever 102 air pressure is supplied to the lower part of the cylinder so as to lift the piston. When the cam permits, the spring pushes the valve out, and air pressure is admitted to the top of the cylinder so as to lower the piston and force the plunger 85 down. The valve may be closed by hand by turning the handle 114 on the end of the vertical shaft 105 mounted in the bracket 106, so as to swing the latch 107 against the lever 102 (Figs. 2, 16 and 19). This prevents the lever from moving and holds the valve 113 closed.

As previously stated, the cam 47 acting against the roll 46 on the lever 43 operates the table lock bolt, and the cam 104 acting against the roll 103 on the lever 102 actuates the piston controlling air valve 113. The stud 108 for the roll 46 and the stud 109 for the roll 103 are extended and halved so that they can engage with each other (Figs. 8, 9). Consequently if for any reason the lock bolt is held back out of a notch these studs engage and the plunger controlling valve 113 is held so that the plunger will be held up. The parts are thus interlocked, so that unless the lock bolt has entered a notch and locked the table in proper position the plunger cannot descend. And as the lock bolt

holds out the rotator bolt when the table is out of proper relation to the rotating mechanisms, the plunger will not descend until the relations are restored, so that the table will be stationed correctly for the plunger 70 to enter a mold.

Interlocking devices are also provided between the piston rods 84 and the table rotating mechanisms, so that if either plunger should fail to rise on account of sticking in its mold, or by reason of the failure of the air pressure supply, the table rotating means will be disconnected, so that the associated table will not be moved and thus break its pressing mechanism. To accomplish this, vertical rods 110 are mounted so as to move vertically in front of the machine. Each rod is connected by a spring 111 and the two collars 112 with an arm 124 that is attached to the piston rod 84 (Fig. 85 1) and is thus moved up and down by the piston rod. Near its lower end each rod 110 carries two dogs 115 and 116 (Figs. 13, 14). Mounted to turn on a stud 93, fixed in a bracket 117 fastened to the post 118 is a bell crank lever 119, carrying a latch 125 at its lower end. A spring 120 is arranged to draw the end of this lever 119 down and normally hold its latch 125 over a dog 126 attached to the front side of the treadle 95 bar 58 (Figs. 12, 13, 14). As the piston rod 84 moves to its upper position, the dog 115 engages a pin 122 projecting from a side of the bell crank lever 119 and lifts that end of the lever so that its latch 125 will 100 be carried away from the dog 126 (Fig. 14), thus allowing the treadle lever to rise and the controller 36 to be moved out so that the rotator bolt may enter a notch 28 and turn the table. In the normal operation of the machine the plunger rises clear of its mold before releasing the latch 125 from the treadle 59, and thus permits the rotator bolt 26 to enter one of the notches and turn the table. If, however, the plunger 110 should adhere to the glass, or for any reason fail to rise above the mold, the latch will not release the treadle and the controller 36, so that the latter will continue to hold the rotator bolt in its retracted position, and the table will not advance (Fig. 117). If for any reason the plunger should descend while the table is turning, as for example by the failure of the air supply, the dog 116 will engage a pin 123 that projects from the treadle bar and force it down and by its connecting rod 55 cause a withdrawal of the rotator bolt from engagement with the table (Figs. 12, 13, 14).

Means are usually provided for cooling 125 the presser plunger 85 to prevent it from being overheated by repeated contact with the hot glass. A supply of air or other cooling fluid under pressure is conducted to the inner plunger through the pipe 135 leading 130

from any suitable supply. Provision is made for controlling the flow of cooling fluid to the plunger in conjunction with the operation of the pressing mechanism. For this purpose the pipe 135 leads through the valve 136 (Figs. 2, 15, 16 and 19). That valve is supported by the bracket 106, with its turning plug 137 in engagement with a slotted collar 138 on the lower end of the shaft 105, so that the latter opens and closes the valve when the latch 107 is open and closed. Thus the cooling fluid is supplied to the plunger 85, when the latch is open, as shown in Fig. 15, to permit the normal operation of the pressing mechanism, and is shut off when the latch is closed (Figs. 16, 19) to stop the plunger operations.

The gears 140 and 141 (Figs. 5 and 7) form no part of the present invention, being employed for transmitting motion from the worm gear 10 to blank transferring or other auxiliary mechanism sometimes employed with this machine.

The mechanism thus far described relates to machines for producing glassware which is pressed, and not blown. For adaptation to a machine in which the glassware is also blown, as well as pressed, suitable blow molds and blowing heads of any ordinary and well-known construction, may be provided. The admission of the air pressure for operating the blow heads in such cases may be controlled and coördinated with the mechanism above described, by means of a piston valve 128 arranged in the valve chest 100 below the valve 113, and similar in construction and arrangement thereto. It is positively operated in one direction against the pressure of a spring like the spring 101, by the angle lever 129 pivotally mounted on the post 44 below the angle lever 102, and provided with a cam roll 130, which is engaged by the cam 131 on the cam shaft 32. The valve chest is connected with the blow head mechanism by pipes from the outlets 132. The operations of the blow heads are thus controlled in proper time relation to the pressing mechanism and to its controlling devices previously described.

The interlocking system above described is extended to the blow head controlling mechanism by means of the latch 133, similar to the latch 107, and similarly fastened to the shaft 105, so that the blow head operating mechanism will be latched out of operation coincidently with the similar latching out of the pressing mechanism.

In the normal operation of the machine, the two mold tables are intermittently advanced by alternate movements of their advancing mechanisms shown in Figs. 2, 3 and 4, the charges of glass being fed to the molds at one station and pressed by the

plunger 85 at another station, both while the mold tables are at rest. During this normal operation, the lock bolt releasing lever 51-52 and the latches 61, 107 and 133 remain in their retracted positions. The latch 125 is at each downward movement of the plunger automatically moved to its latching position (Fig. 13) over the dog 126 on the treadle 59, the latter being at that time in its lowest position, to which it is moved by its connection with the controller 36 in the regular operation of the cam 34. When the plunger rises safely the latch 125 is withdrawn, thus permitting continued movement of the controller 36, and the continued advance of the mold table.

If it is desired to stop the pressing operations without stopping the table movements, the latches 107, 133 are manually turned by means of the handle 114, thus latching the valves 113 and 128 in their closed position, and also shutting off the flow of cooling fluid to the plunger, by the valve 136.

When it is desired to stop the advancing movement of the table, the latch 61 is manually turned to its latching position shown in Fig. 14 by means of the handle 62. This leaves the locking bolt mechanism free to lock the table at any of its stopping stations. When it is desired to stop the entire machine, including the table locking mechanism, the lever 51-52 is manually turned to the position shown in Figs. 4, 6 and 15, which by means of the latch 48 holds the controller 36 out of operation and by means of the interlocking heads of the studs 108 and 109 (Figs. 9 and 18) also holds the plunger controlling valve 113 closed. Throughout any of these uses of the interlocking stops of one mold table, its companion mold table may continue its normal operation and production.

The mold supporting table 4 which is herein shown as a flat topped circular bed or table, may be of any of the various forms well known in this art, sometimes consisting of arms, or otherwise more or less skeleton in form. Functionally, it is a mold support; but is herein described as a table, for the sake of brevity.

Various well-known constructions and arrangements of the piston valves, their ports and passages, and the pipes for admitting air from the source of supply to the valve chest, and for conducting the air from the valves to the cylinder and to the blow heads, may be employed, such details being adapted to various requirements by the expected skill of designers and mechanics familiar with this art. In like manner the various constructions and arrangements here shown may be inverted or transposed and otherwise modified and adapted to suit various conditions and requirements of service.

The invention claimed is:—

1. In a glass shaping machine, the combination of a rotatable mold support, mechanism for turning said support, mechanism for locking said support, and means intermediate the said two mechanisms and controlled by the position of locking mechanism, to render ineffective the support turning mechanism. 5
2. In a glass shaping machine, the combination of a rotatable mold table, mechanism for turning said table, a reciprocatory presser, mechanism for moving the presser toward and from said table, mechanism for locking the said table between its movements, and mechanism intermediate the table turning mechanism and each of the other two adapted to render the table turning mechanism ineffective upon the abnormal positioning of one of the other two mechanisms. 10
3. In a glass shaping machine, the combination of a rotatable mold table, an alternately oscillating and stationary rotator bolt adapted to engage and turn said table, means for moving the bolt into and out of engagement and coacting mechanism adapted to prevent the bolt moving means from moving the bolt into engagement during the oscillation of the bolt. 15
4. In a glass shaping machine, the combination of a rotatable mold table, mechanism for turning said table, mechanism for locking said table between its turning movements, presser mechanism, and mechanism intermediate the table turning mechanism, and the presser mechanism and controlled by the locking mechanism, to render the table turning and presser mechanisms ineffective when the table locking mechanism fails to properly perform its functions. 20
5. In a glass shaping machine, the combination of a rotatable mold table, mechanism for turning said table, mechanism for locking said table between its turning movements, presser mechanism, and manually operated means for releasing the locking mechanism and causing the locking mechanism to obstruct the action of the table turning mechanism and stop the action of the presser reciprocating mechanism. 25
6. In a glass shaping machine, the combination of a rotatable mold table, an oscillatory bolt for intermittently turning said table, a reciprocatory bolt for locking said table between its movements, a reciprocatory plunger movable toward and from the mold table, and manually operated means for rendering inactive the lock bolt, the table turning bolt and the plunger. 30
7. In a glass shaping machine, the combination of a rotatable mold table, mechanism for intermittently turning said table, mechanism for locking said table between its movements, a reciprocatory presser, mechanism for intermittently moving said presser toward and from the mold table, a treadle movable with the table turning mechanism, and manually operated means for locking the treadle against movement and rendering inactive the table turning mechanism. 35
8. In a glass shaping machine, the combination of a rotatable mold table, mechanism for intermittently turning said table, mechanism for locking said table between its movements, and means actuated by the failure of the locking mechanism to lock the table in normal position, to render the table rotating mechanism ineffective. 40
9. In a glass shaping machine, the combination of a rotatable mold table, an oscillatory bolt for intermittently turning said table, a reciprocatory bolt for locking said table between its movements, and means controlled by the abnormal position of the locking mechanism, to render the table turning mechanism ineffective. 45
10. In a glass shaping machine, the combination of a rotatable mold table, an oscillatory bolt for intermittently turning said table, a reciprocatory bolt for locking said table between its movements, a lever for actuating the lock bolt, and means carried by said lever and operable upon the abnormal position of the locking mechanism, to render the table turning bolt ineffective. 50
11. In a glass shaping machine, the combination of a rotatable mold table, a rotator bolt for intermittently turning said table, a controller for releasing said bolt from the table, a reciprocatory lock bolt for locking said table between its movements, a lever for actuating the lock bolt, and means carried by the lock bolt lever and holding the controller in its bolt releasing position when the lock bolt fails to lock the table. 55
12. In a glass shaping machine, the combination of a rotatable mold table, mechanism for intermittently turning said table, locking mechanism for locking said table between its movements, and manually controlled means for releasing said locking mechanism and rendering ineffective the table turning mechanism. 60
13. In a glass shaping machine, the combination of a rotatable mold table, mechanism for intermittently turning said table, mechanism including a table lock for locking said table between its movements, and manually controlled means for coincidentally releasing said table lock and rendering ineffective the table turning mechanism. 65
14. In a glass shaping machine, the combination of a rotatable mold table, an oscillatory rotator bolt for intermittently turning said table, a reciprocatory lock bolt for locking said table between its movements, 70
15. In a glass shaping machine, the combination of a rotatable mold table, an oscillatory bolt for intermittently turning said table, a reciprocatory lock bolt for locking said table between its movements, and means actuated by the failure of the locking mechanism to lock the table in normal position, to render the table rotating mechanism ineffective. 75
16. In a glass shaping machine, the combination of a rotatable mold table, an oscillatory bolt for intermittently turning said table, a reciprocatory lock bolt for locking said table between its movements, and means controlled by the abnormal position of the locking mechanism, to render the table turning mechanism ineffective. 80
17. In a glass shaping machine, the combination of a rotatable mold table, an oscillatory bolt for intermittently turning said table, a reciprocatory lock bolt for locking said table between its movements, and means carried by the lock bolt lever and holding the controller in its bolt releasing position when the lock bolt fails to lock the table. 85
18. In a glass shaping machine, the combination of a rotatable mold table, a rotator bolt for intermittently turning said table, a controller for releasing said bolt from the table, a reciprocatory lock bolt for locking said table between its movements, a lever for actuating the lock bolt, and means carried by the lock bolt lever and holding the controller in its bolt releasing position when the lock bolt fails to lock the table. 90
19. In a glass shaping machine, the combination of a rotatable mold table, mechanism for intermittently turning said table, locking mechanism for locking said table between its movements, and manually controlled means for releasing said locking mechanism and rendering ineffective the table turning mechanism. 95
20. In a glass shaping machine, the combination of a rotatable mold table, a rotator bolt for intermittently turning said table, a controller for releasing said bolt from the table, a reciprocatory lock bolt for locking said table between its movements, a lever for actuating the lock bolt, and means carried by the lock bolt lever and holding the controller in its bolt releasing position when the lock bolt fails to lock the table. 100
21. In a glass shaping machine, the combination of a rotatable mold table, a rotator bolt for intermittently turning said table, a controller for releasing said bolt from the table, a reciprocatory lock bolt for locking said table between its movements, a lever for actuating the lock bolt, and means carried by the lock bolt lever and holding the controller in its bolt releasing position when the lock bolt fails to lock the table. 105
22. In a glass shaping machine, the combination of a rotatable mold table, mechanism for intermittently turning said table, locking mechanism for locking said table between its movements, and manually controlled means for releasing said locking mechanism and rendering ineffective the table turning mechanism. 110
23. In a glass shaping machine, the combination of a rotatable mold table, mechanism for intermittently turning said table, mechanism including a table lock for locking said table between its movements, and manually controlled means for coincidentally releasing said table lock and rendering ineffective the table turning mechanism. 115
24. In a glass shaping machine, the combination of a rotatable mold table, an oscillatory rotator bolt for intermittently turning said table, a reciprocatory lock bolt for locking said table between its movements, 120
25. In a glass shaping machine, the combination of a rotatable mold table, an oscillatory rotator bolt for intermittently turning said table, a reciprocatory lock bolt for locking said table between its movements, and means actuated by the failure of the locking mechanism to lock the table in normal position, to render the table rotating mechanism ineffective. 125

and mechanism for coincidently releasing said lock bolt and said rotator bolt from the table.

15. In a glass shaping machine, the combination of a rotatable mold table, an oscillatory rotator bolt for intermittently turning said table, a reciprocatory lock bolt for locking said table between its movements, interlocking means between the two bolts, 5 and manually controlled mechanism for coincidently releasing said lock bolt from the table and through the said interlocking means to prevent the table turning action of the rotator bolt.

15. 16. In a glass shaping machine, the combination of a rotatable mold table, mechanism for intermittently turning said table, mechanism for locking said table between its movements, a reciprocatory presser, 10 mechanism for intermittently moving the presser toward and from the mold table, and mechanism operated by the failure of the locking mechanism to lock the table, to stop the presser in a position clear of the 25 molds on the table.

17. In a glass shaping machine, the combination of a rotatable mold table, mechanism for intermittently turning said table, mechanism for locking the table between its 30 movements, and means between the said mechanisms and controlled by the position of the locking mechanism for arresting the normal operation of the table turning mechanism when the locking mechanism is in 35 abnormal position.

18. In a glass shaping machine, the combination of a rotatable mold table, a rotator bolt intermittently engaging and turning said table, a lock bolt engaging and locking 40 said table between its movements, mechanism for releasing said lock bolt from the table, and interlocking mechanism preventing the rotator bolt from engaging with the table when the lock bolt fails to normally 45 lock the table.

19. In a glass shaping machine, the combination of a rotatable mold table, a rotator bolt intermittently engaging and turning said table, a lock bolt engaging and locking 50 said table between its movements, mechanism for releasing said lock bolt from the table, and interlocking mechanism connected with the lock bolt and the rotator bolt and preventing the rotator bolt from engaging 55 the table for a turning movement until the lock bolt has locked the table after its previous turning movement.

20. In a glass shaping machine, the combination of a rotatable mold table, a rotator bolt intermittently engaging and turning 60 said table, mechanism controlling the engagement of said bolt with the table, a lock bolt for engaging and locking the table between its movements, mechanism for releas-

ing said lock bolt from the table, and mechanism carried by the lock bolt releasing mechanism and adapted to engage the rotator bolt controller mechanism and retain the rotator bolt out of engagement with the table until the lock bolt has locked the table. 65

21. In a glass shaping machine, the combination of a rotatable mold table, mechanism for intermittently turning said table, mechanism for locking the table, a reciprocatory presser, mechanism for intermittently 70 moving the presser toward and from the mold table, and mechanism actuated by the locking mechanism for preventing the operation of the presser reciprocating mechanism unless and until the locking mechanism 75 has locked the table.

22. In a glass shaping machine, the combination of a rotatable mold table, mechanism for intermittently turning said table, mechanism for locking the table, a reciprocatory presser, an air cylinder for intermittently moving the presser toward and from the mold table, an air valve controlling the admission of air pressure to said cylinder, a cam for operating said valve, means controlled by the locking mechanism for holding said valve closed unless and until said locking mechanism has properly locked the 80 table. 85

23. In a glass shaping machine, the combination of a rotatable mold table, mechanism for intermittently turning said table, a bolt for engaging and locking the table, mechanism for disengaging the lock bolt from the table, a reciprocatory presser, an air cylinder for intermittently moving the presser toward and from the mold table, an air valve controlling the admission of air pressure to said cylinder, and means independent of the lock bolt for operating said 100 valve, said lock bolt disengaging mechanism 105 obstructing the air admission movement of said valve operating means unless and until the lock bolt has locked the table. 90

24. In a glass shaping machine, the combination of a rotatable mold table, mechanism for intermittently turning said table, mechanism for locking said table between its movements, a brake adapted to retard the movements of the table, and mechanism for automatically applying the brake during a 110 part of each movement of the table. 115

25. In a glass shaping machine, the combination of a rotatable mold table, mechanism for intermittently turning said table, mechanism for locking said table between its movements, a brake adapted to retard the movement of the table, means for adjusting the tension of the brake, and mechanism for automatically applying the brake 120 during a part of each movement of the table. 125

26. In a glass shaping machine, the combination of a rotatable mold table, mech-

anism for intermittently turning said table, a brake adapted to retard the movements of the table, mechanism for automatically applying the brake during a part of each 5 movement of the table, and manually operated means for releasing the brake.

27. In a glass shaping machine, the combination of a rotatable mold table, mechanism for intermittently turning said table, a 10 band brake encircling the table and adapted to retard the movement of the table, means for adjusting the tension of the brake, mechanism for automatically applying the brake during a part of each movement of the 15 table, and manually operated means for releasing the brake.

28. The combination of two glass shaping machines, each having a rotatable mold table, mechanism for intermittently turning the 20 tables alternately, mechanism for locking each table between its movements, a single driving mechanism for actuating the table rotating mechanisms, and manually controlled means for stopping the effective 25 operation of the mechanisms of either machine without affecting the operation of the mechanism of the other machine.

29. In a glass shaping machine, the combination of a mold table rotatable from station 30 to station, a rotator bolt for advancing the table, mechanism for operating the said bolt to engage and advance the table, and controlling mechanism for the table engaging movements of the bolt, adapted to prevent 35 the engaging action of the bolt whenever the table is between stations.

30. In a glass shaping machine, the combination of a mold table adapted to rotate between stationary locking positions, a rotator bolt for advancing the table, mechanism 40 operating the bolt to engage and advance the table, a movable controller for the table engaging movements of the mold, means for operating the controller to move the bolt 45 into and out of engagement with the table, and means adapted to prevent the bolt being moved into engagement whenever the table is between its stationary locking positions.

31. In a glass shaping machine, the combination of a rotatable mold table, a table lock to lock the table between its movements, a rotator bolt for advancing the table, mechanism 50 operating the bolt to engage and advance the table, a movable controller for the table engaging movements of the bolt having a bolt guiding surface disposed in concentric relation to the center of table 55 rotation when holding the bolt disengaged from the table, and means for latching the controller in that position by the unlocking of the table lock.

32. In a glass shaping machine, the combination of a rotatable mold table, a rotator bolt for advancing the table, mechanism

operating the bolt to engage and advance 65 the table, a controller for the table engaging movements of the bolt, having a bolt guiding surface disposed in concentric relation to the center of table rotation when in position for holding the bolt disengaged from 70 the table, a table locking bolt, mechanism for operating the locking bolt, and latching means coacting with the locking mechanism to latch the controller in and unlatch it from its said concentric position. 75

33. In a glass shaping machine, the combination of presser mechanism including a pressing plunger, connections including a valve for supplying a cooling fluid to the plunger, and coacting mechanism for stopping the normal operations of the plunger 80 and coincidentally closing the valve.

34. In a glass shaping machine, the combination of presser mechanism including a pressing plunger and a pressure cylinder 85 for operating said plunger, connections for supplying its operating fluid pressure to the cylinder, and a cooling fluid to the plunger, and coacting valve mechanism for stopping the normal operations of the plunger 90 and coincidentally stopping the admission of cooling fluid to the plunger.

35. In a glass shaping machine, the combination of presser mechanism including a pressing plunger and a pressure cylinder 95 for operating said plunger, connections for supplying its operating fluid pressure to the cylinder, and a cooling fluid to the plunger, valves controlling the admission of the pressure fluid and the cooling fluid 100 respectively, and co-operative connections between the said valves, whereby the cooling fluid is shut off from the plunger when the pressure fluid is shut off from the cylinder to stop the normal operations of the plunger. 105

36. In a glass shaping machine, the combination of presser mechanism including a plunger and a pressure cylinder for operating said plunger, connections for supplying fluid pressure to the cylinder, and for supplying cooling fluid to the plunger, a valve controlling the admission of the pressure fluid to the cylinder, mechanism moving the said valve in its normal operations, a manually operated valve controlling the admission of the cooling fluid to the plunger and means operative with the last named valve arranged to latch the pressure controlling valve and stop the normal operation of the plunger, when the cooling fluid is shut off 110 from the plunger. 120

37. In a glass shaping machine, the combination of presser mechanism including a plunger and a pressure cylinder for operating said plunger, connections for supplying fluid pressure to the cylinder, and for supplying cooling fluid to the plunger, a valve controlling the admission of the pres- 125

- sure fluid to the cylinder, mechanism moving the said valve in its normal operations, a valve controlling the admission of the cooling fluid to the plunger, and a manually operated latch device arranged to latch the first named valve out of normal operation and operatively connected with the second named valve to coincidently stop the admission of cooling fluid to the plunger.
- 10 38. The combination of two glass shaping machines, each having a rotatable mold table, mechanism for intermittently turning the tables alternately, a reciprocatory presser for each table, mechanism for intermittently moving each presser toward and from the mold table, mechanism for locking each table between its movement, a single driving mechanism for actuating the table rotating and presser reciprocating mechanisms of the two machines, and means for stopping the effective operation of the mechanisms of either machine independently of the operation of the mechanisms of the other machine.
- 15 39. The combination of two glass shaping machines, each having a rotatable mold table, mechanism for intermittently turn-

ing the tables alternately, a reciprocatory presser for each table, mechanism for intermittently moving each presser toward and from the mold table, a single driving mechanism for actuating the table rotating and presser reciprocating mechanisms of the two machines, and manually controlled means for stopping the effective operation of the mechanisms of either machine without effecting the operation of the mechanisms of the other machine.

20 40. The combination of two glass shaping machines, each having a rotatable mold table, mechanism for alternately turning each table, mechanism for locking each table between its movements, a single driving mechanism for actuating the table rotating and the locking mechanisms in alternation, and manually controlled means for stopping the effective operation of the mechanisms of either machine independently of the operation of the mechanisms of the other machine.
